Benjamin Williamson

Letters Patent

The schedule is referred to in these Letters Patent and making part of the same containing a description in the words of the said Benjamin Williamson himself of his improvement in the Gum Elastic Truss for Hernia.

Specification of the Gum Elastic Truss for the Original Hernia

This Truss is composed of Gum Elastic without any metallic substance being connected with it. It is formed of a piece of Gum Elastic about two inches in breadth at one end, and about two inches and one half inches in breadth at the other end curving in a semi-circular form being varied in size in proportion to the size of the subject to which it is to be applied. Comes on the inside and some of them with two coverings with a concave groove between them and some of them flat on the inside. From this semi-circular pad proceeds a cord of the same substance which passes down around the thigh and is attached to the upper and outer angle of the scrotum pad. So that this cord holds the lower edge as well as the lower angle of the pad close down as well as makes pressure against the lower part of the abdomen below and over the abdominal ring through which the protrusion comes. From the upper and outer angle of the pad a little above the place where the cord that passes around the thigh is fastened commences a band about one inch and one half inch in breadth of the same substance. or this band must be varied in size as upon the elasticity of this band depends the pressure applied to the upper portion of the pad. Therefore in some instances this band may have to be strengthened by being made larger and in some cases a web of cloth may be used instead of the Gum Elastic band when it requires greater strength to keep off the hernia than in ordinary cases. This band passes around the body and the cord is fastened to the scrotum pad by a Gum Elastic Button and button holes in the band so as to fasten the band in front upon the pad or

the band may be attached ~~permanently~~ to the pad so as to make it entirely whole a smaller sized ^{band} is attached to the cord that passes around the thigh and goes back from 3 to eight inches in an angle and is fastened to the band that goes around the body so as to make extension upon this cord keeping it close to the inside of the thigh and groin. At the junction of the Pad and band that goes around the body commences a second cord and goes down and is attached to the cord that goes around the thigh below where the small band is fastened to the first cord - For a double truss the pad is made large enough to extend across the lower portion of the abdomen so as to cover over and extend out on either side beyond the abdominal ring. made like unto two single trusses ^{united} by uniting them from right and left being wholi in the centre and being suspended and kept to its place by the gum elastic bands and cords in like manner as the single truss is already described. This double truss may also be applied to females to support and give strength to the lower portion of the abdomen in case of the falling of the uterus with the following variations to wit. The pad is ~~to be~~ made so wide & extended so high as to fill the hypogastric region of the abdomen and applied and retained in its place by the bands and cords as first described.

For Umbilical Hernia - The pad is of an oval shape its length to be applied up and down, a flat band to be attached to one side of the rupture pad and to pass around the body and to button ^{up} on the opposite side of the pad by means of buttons and button holes, or maybe permanently attached. These trusses are all to be covered with cloth except under the rupture pad. This may be covered or not.

The applicant claim to have invented and used on his own person a truss made by himself of the substance and of one of the forms above described sometimes before he heard of the construction of any part of a truss made of the same substance by any other person. On or about the first day of August last he was informed that doctor McIntyre man had a patent for a truss upon the old plan of spring and pads, and that the rupture pad was covered with or in some ^{way}

of gum elastic with a spiral spring in the centre but this
apparatus has now gone. The applicants invention differs
from all others in being known to him in being constructed of gum elastic
tie and being kept in its place by means of the bands and ends without
the use of any metallic or wooden substance. The said being also
of a different and new shape as above described.
